UNITED STATES PATENT OFFICE

FRANCIS J. CARNELLI, OF NEW YORK, N. Y.

CHAIN WRENCH

Application filed October 25, 1930. Serial No. 491,124.

This invention relates to wrenches of the chain type in which the wrench is provided with jaw portions at the end of the handle, and a link chain is passed around a pipe engaged by these jaws, and the chain secured to the body just back of the jaws, usually in an adjustable manner. It is customary to provide a pair of spaced plates or projections to constitute these jaw members, and further to provide teeth on these portions, and each jaw plate is frequently made angular with the apex at the middle, in line with the handle axis, from which angular portions of the jaws extend, diverging outwardly.

15 The object of the present invention is to provide an improved form of jaws at the end, whereby the pipe can be placed at the middle portion that is somewhat depressed, and then the chain made secure to the body 20 after passing around the pipe, and as the wrench handle is swung in either direction, the side portions of the jaw plates will have a particular cam action on the pipe, by taking up the small amount of slack in the chain 25 after it has been secured to the body.

In the accompanying drawings showing embodiments of my invention,

Figure 1 is a side elevation of the wrench.

Fig. 2 is a similar view at the end portion 30 after the pipe has been engaged and the handle swung to clamping position.

Fig. 3 is a view taken at a right angle to that of Fig. 1.

Figs. 4 and 5 show the jaw plates detached.

Fig. 6 shows the end of the handle bar.

Fig. 7 is an end view partly in section.

Fig. 8 is a cross section on the line 8—8 of Fig. 1.

Fig. 9 is a diagram taking the relative 40 shape and position of the jaw plate ends.

Fig. 10 shows another form of nut and slotted portions of the plates.

As shown in the drawings the wrench comprises a body consisting of a handle 2 and jaw members or plates 3 and 4, that are suitably secured to the end of the handle as by a bolt 5 passing through holes 6 and 7 in the plates and a hole 8 in the handle portion. These plates have slotted portions at 9 and 10 into 45 which fits the squared end of the handle to

prevent turning of the plates, and the bar is shown provided with lugs at 11 and 12 that engage the rear edge of the plates respectively to receive the end thrust of the plates on the bar, and thus relieve strain on the bolt 5. 55

Any suitable means may be employed to secure the link chain 13 to the body, preferably to the plates, and which may be adjustable to accommodate different sizes of pipes. As shown each plate is provided with a hook 60 projection 14, 15, on its inner face extending outwardly and rearwardly, to receive pins 16 on the chain 13, that project out beyond the links as indicated in Fig. 8. The other end of the chain is shown adjustably secured by 65 means of a threaded bolt 17 engaged by a nut 18 that turns in slotted portions 19 and 20 in the plates 3 and 4, which nut will project outwardly through these slots for engagement by the fingers of the user, and the bolt and 70 chain can travel endwise between the separated plates. Where various sizes of pipes are engaged, the chain, after passing around the pipe, will be brought further out from the axial line of the handle, or nearer, and thus an 75 angular strain would be exerted on this adjusting bolt, tending to twist it in the nut as the latter remained with its axis parallel with the handle axis. To permit this nut to swing I provide it with a curved or spherical face 21, 80

and the edges or walls of the plates 3 and 4 engaged by this curved nut face are curved or spherical as at 22 and 23. Instead of the spherical face of the nut and similar convex curves of the engaging faces of the plate slots, 85 the nut 40 can have a flat face 41 in a plane, and the slot faces 42 and 43 can be curved as a cylinder as shown in Fig. 10.

The end walls of the plates 3 and 4 constitute the jaws to engage the pipe. In the 90 form shown I provide toothed faces on each side of the middle portion that is depressed, each lying substantially in a curve, as at 24 and 25 in the jaw 3, and 26 and 27 in the jaw 4. In Fig. 9, I indicate a diagram showing the curved arrangement of these jaw faces 24 and 25. These curves as shown have the chords 28 and 29 in alignment or coinciding, and preferably this line is perpendicular to the axis 30 of the handle. I also find it of ad- 95

vantage to form these curves with the center of the curve 24 at 31, where the pin 16 is engaged by the hooks 14 and 15; and the center of the curved face 25 is located at the normal or approximate position of the pivot connection of the bolt 17 with the end link of the chain, as at 32. It will be further observed that these pivot points are equi-distant from the axis 30 of the handle. It will be further observed that a common tangent line 35 to the curves 24 and 25 will have a point of tangency at 36 and 37, at the intersection of the lines 38 and 39 passing through the center 31 and 32 of the curves 24 and 25, and parallel to the handle axis 30.

The jaws 3 and 4 are provided each with an extension 44 and 45 projecting inwardly until they contact as shown in Fig. 7. The end faces of these extensions correspond in contour to the toothed curved jaw portions 24 and 25 of one jaw plate and 26 and 27 of the other jaw plate. Thus it will be seen from Fig. 7 that the jaws are practically continuous from side to side at the inner or middle portions, to better engage the smaller sizes of pipes, as well as to reinforce the jaws, and better engage the flanges or beads on fittings.

In the use of the device a pipe as 23 is placed at the middle portion of the jaw plates containing the depression 34, and the free end of the chain passed around the pipe and brought down to engage the hooks 14 and 15. The nut 18 is adjusted one way or the other so that one of the pins 16 on this end portion of the chain will pass down into the hook portions of the plates. But this will provide a small amount of slack in the chain as the link moves into this hook towards the jaws. As stated the nut is turned until the link can just pass down into the hook after going around the pipe in the middle position, as shown in Fig. 1. Then the handle is swung, as to the left in Fig. 2, and the pipe being stationary the jaw face 23 will turn or swing on the face of the pipe. It will be seen from Fig. 2 that the handle jaw plates will practically swing on the center 31 of the curved jaw face 24, and this portion of the chain will not tighten around the pipe, but as the pipe now moves away from the body or jaw portion of the wrench in an axial direction as well as to one side, the other chain portion being held by the nut will tighten around the pipe and cause it to be gripped by the teeth, and further pressure on the handle will swing the pipe on its axis. It will be further seen that reverse swing of the handle will loosen the chain and the pipe will pass back into the depression between the jaws at 34. This will loosen the wrench on the pipe and it can be swung back to obtain a fresh grip, and then again swinging the wrench to the left it will further turn the pipe, and thus have the ratchet action.

It will be understood that if the wrench is swung to the right relative to the pipe from the position of Fig. 1, the pipe will engage the jaw 25 in the same manner and the operation will be the same, with the ratchet action to turn the pipe.

What I claim is:—

1. In a chain wrench, a body comprising a handle bar, a pair of jaw plates secured at one end of the bar to form a pair of jaws provided with teeth at the end of the wrench, and a link chain connected at pivotal points on opposite sides of the body, each toothed jaw end face on each side of the middle portion extending in the general form of a flat convex curve with the chord of the curve on each side in alignment and transverse to the handle axis.

2. In a chain wrench, a body comprising a handle bar, a pair of jaw plates secured at one end of the bar to form a pair of jaws provided with teeth at the end of the wrench, and a link chain connected at pivotal points on opposite sides of the body, each jaw having a middle depression, each toothed jaw end face on each side of the depression extending in the general form of a flat convex curve with the chord of the curve on each side in alignment and transverse to the handle axis.

3. In a chain wrench, a body comprising a handle bar, a pair of jaw plates secured at one end of the bar to form a pair of jaws provided with teeth at the end of the wrench, and a link chain connected on opposite sides of the body at pivotal points substantially equi-distant from the axis of the handle, each toothed jaw end face on each side of the middle portion extending in the general form of a flat convex curve with the chord of the curve on each side in alignment and transverse to the handle axis.

4. In a chain wrench, a body comprising a handle bar, a pair of jaw plates secured at one end of the bar to form a pair of jaws provided with teeth at the end of the wrench, and a link chain connected on opposite sides of the body at pivotal points substantially equi-distant from the axis of the handle, each jaw having a middle depression, each toothed jaw face on each side of the depression extending in the general form of a flat convex curve with the chord of the curve on each side in alignment and transverse to the handle axis.

5. In a chain wrench, a body comprising a handle bar, a pair of jaw plates secured at one end of the bar to form a pair of jaws provided with teeth at the end of the wrench, and a link chain connected adjustably at pivotal points on opposite sides of the body at points substantially equi-distant from the axis of the handle and which points are in a line perpendicular to the handle axis, each toothed jaw end face on each side of the middle portion extending in the general form of a flat convex curve with the chord of the curve on each side in alignment and transverse to the handle axis.

a flat convex curve with the chord of the curve on each side in alinement and transverse to the handle axis.

6. In a chain wrench, a body comprising a handle bar, a pair of jaw plates secured at one end of the bar to form a pair of jaws provided with teeth at the end of the wrench, and a link chain adjustably connected on opposite sides of the body at pivotal points on opposite sides of the body at points substantially equi-distant from the axis of the handle and which points are in a line perpendicular to the handle axis, each jaw having a middle depression, each toothed jaw and face on each side of the depression extending in the general form of a flat convex curve with the chord of the curve on each side in alinement and transverse to the handle axis.

7. In a chain wrench, a body comprising a handle bar, a pair of jaw plates secured at one end of the bar to form a pair of jaws provided with teeth at the end of the wrench, and a link chain adjustably connected on opposite sides of the body at pivotal points substantially equi-distant from the axis of the handle, each toothed jaw and face on each side of the middle portion extending in the general form of a flat convex curve in which a tangent line common to the two curves of each jaw will intersect at the point of tangency of each curve, a line passing through the pivotal connection of the chain on that side of the handle axis and which latter line on each side is parallel to the handle axis.

8. In a chain wrench, a body comprising a handle bar, a pair of jaw plates secured at one end of the bar to form a pair of jaws provided with teeth at the end of the wrench, and a link chain adjustably connected on opposite sides of the body at pivotal points substantially equi-distant from the axis of the handle, each jaw having a middle depression, each toothed jaw end face on each side of the depression extending in the general form of a flat convex curve in which a tangent line common to the two curves of each jaw at the point of tangency of each curve will intersect a line passing through the pivotal connection of the chain on that side of the handle axis and which latter line on each side is parallel to the handle axis.

9. In a chain wrench, a body comprising a handle bar, a pair of jaw plates secured at one end of the bar to form a pair of jaws provided with teeth at the end of the wrench, and a link chain adjustably connected on opposite sides of the body at pivotal points in a line perpendicular to the handle axis, and substantially equi-distant from such axis, each toothed jaw end face on each side of the middle portion extending in a curve in which a tangent line common to the two curves of each jaw at the point of tangency of each curve will intersect a line passing through the pivotal connection of the chain on that

side of the handle axis, and which latter line on each side is parallel to the handle axis.

10. In a chain wrench, a body comprising a handle bar, a pair of jaw plates secured at one end of the bar to form a pair of jaws provided with teeth at the end of the wrench, and a link chain adjustably connected on opposite sides of the body at pivotal points in a line perpendicular to the handle axis, and substantially equi-distant from such axis, each jaw having a middle depression, each toothed jaw end face on each side of the depression extending in a curve in which a tangent line common to the two curves of each jaw at the point of tangency of each curve will intersect a line passing through the pivotal connection of the chain on that side of the handle axis, and which latter line on each side is parallel to the handle axis.

Signed at New York city, N. Y., on October 24, 1930.
